WINDOW MOUNTED ROOM AIR CONDITIONER

Webster B. Harpman, Poland, Ohio

Application June 1, 1956, Serial No. 41,722

Term of patent 14 years

(Cl. D62—4)

The bottom is substantially plain.

I claim:

The ornamental design for a window mounted room air conditioner, as shown and described.
